UNITED STATES PATENT OFFICE.

WILLIAM J. TRESNAK, OF LAKE WORTH, FLORIDA.

ROWLOCK.

Application filed June 30, 1922. Serial No. 571,954.

To all whom it may concern:

Be it known that I, WILLIAM J. TRESNAK, a citizen of the United States of America, residing at Lake Worth, in the county of 5 Palm Beach and State of Florida, have invented certain new and useful Improvements in Rowlocks, of which the following is a specification.

This invention relates to certain new and 10 useful improvements in row locks and has particular reference to a row lock embodying a universal joint for supporting an oar above the gunwales of the boat.

The primary object of the invention re- 15 sides in the provision of a row lock embodying a universal joint, a part of which joint is permanently connected to the oar, while the remaining portion of the joint is carried by the gunwale of the boat.

20 The invention further includes in a row lock of the type above set forth, a pivotally mounted bracket arm constituting a portion of the universal joint of the row lock with means for holding the bracket arm in the 25 position for properly supporting the remaining portion of the universal joint.

With the above general objects in view and others that will appear as the nature of the invention is better understood, the same 30 consists of the novel form, combination and arrangement of parts hereinafter more fully described, shown in the accompanying drawing and claimed.

In the drawing, wherein like reference 35 characters designate corresponding parts,

Figure 1 is a side elevational view, partly in section of a row lock and mounting therefor constructed in accordance with the present invention, the row lock being shown by dotted lines in its reducing position to permit

removal of the oar and that part of the universal joint carried by the oar and further showing the locking lever arm for the bracket of the universal joint,

45 Figure 2 is a top plan view of the row lock,

Figure 3 is bottom plan view of the locking lever arm detached from the row lock,

50 Figure 4 is a detail sectional view taken on line IV—IV of Fig. 1 showing the foot carried by the locking lever overlying the leg of the row lock bracket arm,

55 Figure 5 is a detail sectional view, similar to Fig. 4, looking in the opposite direction, and with the locking lever swung to

its open position with the leg of the bracket arm elevated.

Figure 6 is a detail sectional view taken on line VI—VI of Fig. 2 showing the pivotal mounting for the locking arm,

60 Figure 7 is a detail sectional view taken on line VII—VII of Fig. 1 showing the latch button or knob carried by the outer end of the locking lever, and

65 Figure 8 is a bottom plan view of the latch device or locking button detached from the locking lever.

Referring more in detail to the accompanying drawing, there is illustrated a row lock embodying a mounting base frame 1 adapted to be suitably secured to the gunwale of a boat, having a face plate 2 suitably secured to the upper face thereof supporting the row lock mechanism.

70 As shown more clearly in Figs. 1, 2 and 7, the face plate 2 carries a pair of perpendicularly extending spaced blocks 3 substantially intermediate the ends of the plate, while a pair of perpendicularly extending spaced blocks 4 and 5 is positioned adjacent 75 one end of the face plate as illustrated, the upper edge of the block 5 carrying a beveled latch lug 6 shown in Fig. 7. An upwardly extending curved bracket arm 7 is carried by a normally horizontal leg 8 that is preferably formed integral therewith, the forward end of the leg 8 and the lower end of the curved bracket arm 7 at their angle connection being guided between the blocks 3. The outer end of the leg 8 is pivotally 80 mounted on the pin 9 extending between the blocks 4 and 5 while the terminal outer end of said leg is curved as at 10, shown in Fig. 1, to permit pivotal movement on said pin 9.

85 As shown more clearly in Fig. 1, a universal joint supporting an oar 11 is associated with the face plate 2 and the upper end of the curved bracket arm 7, a strap bearing 12 having a bolt 13 journaled transversely 90 thereof that freely extends through an opening in the oar 11 to permit free pivotal movement of the oar on said bolt. The lower side of the strap bearing 12 carries a pin 14 that is

95 freely rotatable in a socket bearing 15 formed in the adjacent end of the face plate 2, a pin 16 carried by the upper side of the strap bearing 12 being associated with the upper end 100 of the curved bracket arm 7. The free end 105 of the bracket arm 7 is provided with a 110

threaded perpendicular bore within which a screw plug 17 is adjustably mounted, said plug having a socket in the lower side thereof for receiving the bearing pin 16 upon 5 the upper side of the strap bearing, said screw block 17 being adjustable in the threaded bore by the finger ring 18 and maintained in adjusted position by the set nut 19. With the strap bearing 12 positioned 10 as illustrated by full lines in Fig. 1, the same is permitted to move on a vertical axis, while the bolt 13 extending transversely of the strap bearing provides free vertical movement of the oar 11 during the swinging or 15 rowing motion thereof.

A locking and shifting device for the leg 8 and curved bracket arm 7 carried thereby is provided, and includes a perpendicular stub shaft 20 carried by the face plate 20 2 adjacent the blocks 3, upon which a sleeve 21 formed integral with and depending from a locking lever 22 is received, the locking lever 22 being pivotally mounted upon the shaft 20 and locked thereon 25 against accidental disengagement by the screw device 23 shown more clearly in Fig. 6. The upper inner end of the locking lever 22 carries an angularly directed foot 24 having a beveled side face 25 adapted 30 for engagement with the beveled edge 26 formed on the upper face of the leg 8 adjacent the sleeve bearing 20 as clearly shown in Figs. 4 and 5. As shown more 35 clearly in Figs. 1, 2 and 4, the lower end of the sleeve 21 carries an extension foot 27 having a beveled side face 28 that is adapted for engaging the beveled lower side edge 29 of the leg 8, while a block 30 depending from said locking lever 22 is adapted for 40 engagement with the leg 8 to permit the closing movement thereof. Fig. 3 of the drawings shows a locking lever 22 detached from the row lock and illustrates the bottom face thereof, showing the angular feet 45 extensions 24 and 27 and the stop block 30. To retain the lever 22 in its locked position, a latch device embodying a head 31 has the shank 32 thereof extending through an opening in the outer end of said locking lever, a flat spring 33 fixed at one end as at 34 to the bottom face of said lever has the free end thereof secured as at 35 to the lower side of the shank 32 of said knob. A latch lug 36 depends from the shank of said knob 50 and is adapted for engagement with the keeper latch lug 6 upon the block 5 as clearly shown in Fig. 7. In the operation of the device, assuming that the row lock mechanism as in the full line position shown 55 in Fig. 1, and it being desired to remove the strap bearing 12 and oar 11 therefrom, the knob 21 is elevated against the tension of the spring 33 to disengage the latch lugs 6 and 36 to permit springing movement of 60 the locking lever 22 upon the stub shaft 20.

During this movement, the foot 27 presents the beveled edge 28 thereof for engagement with the beveled edge 29 upon the lower side of the leg 8, the foot 27 riding beneath said leg to cause upward pivotal movement 70 thereof upon the pin 9, thereby elevating the upper end of the curved bracket arm 7 to permit removal of the pin 16 from the bearing socket in the screw plug 17. In the reverse operation of the device, the foot 75 27 is displaced from engagement with the beveled edge 29 of said leg, and the foot 24 carried adjacent the upper end of said sleeve 21 presents the beveled edge 25 thereof for engagement with the beveled edge 26 80 at the upper side of said leg, thereby depressing the leg and lowering the upper end of the curved bracket arm 7, while the latch device at the outer end of the locking lever cooperating with the keeper lug 6 85 upon the block 5 retains the lever 22 in its locked position.

From the above detail description, it is believed that the construction and operation thereof will at once be apparent, and 90 while there is herein shown and described the preferred embodiment of the present invention, it is nevertheless to be understood that minor changes may be made therein without departing from the spirit 95 and scope thereof as claimed.

What is claimed as new is:—

1. In row lock mechanism, a mounting member, a horizontal leg pivoted thereto, a vertically extending curved bracket arm 100 carried by the free end of said pivoted leg, a universal joint connection for an oar disposed between the mounting plate and the free end of the curved bracket arm, and means for shifting the bracket arm to disconnect the universal joint.

2. In row lock mechanism, a mounting member, a horizontal leg pivoted thereto, a vertically extending curved bracket arm carried by the free end of said pivoted leg, 110 a universal joint connection for an oar disposed between the mounting plate and the free end of the curved bracket arm, and a locking lever pivotally mounted on the mounting member and cooperating with the leg for raising and lowering the curved bracket arm during reverse pivotal movement thereof.

3. In row lock mechanism, a mounting member, a horizontal leg pivoted thereto, 120 a vertically extending curved bracket arm carried by the free end of said pivoted leg, a universal joint connection for an oar disposed between the mounting plate and the free end of the curved bracket arm, and a locking lever pivotally mounted on the mounting member and cooperating with the leg for raising and lowering the curved bracket arm during reverse pivotal movement thereof, said locking lever carrying 130

extensions at the upper and lower sides thereof for engaging said legs to effect movement thereof.

4. In a row lock mechanism, a mounting member, a horizontal leg pivoted thereto, a vertically extending curved bracket arm carried by the free end of said pivoted leg, a universal point connection for an oar disposed between the mounting plate and the 10 free end of the curved bracket arm, a locking lever pivotally mounted on the mounting member and cooperating with the leg for raising and lowering the curved bracket arm during reverse pivotal movement thereof, 15 of, said locking lever carrying extensions at the upper and lower sides thereof for engaging said legs to effect movement thereof, and cooperating means carried by the locking lever and mounting member for holding 20 the lever in its locked position.

5. In row lock mechanism, a mounting member, a normally horizontally disposed leg pivotally mounted thereon, an upwardly extending curved bracket arm carried by 25 the free end of said leg, a universal joint connection for an oar disposed between the mounting member and the upper free end of the bracket arm, a locking lever pivoted on the mounting member, extensions carried 30 by the upper and lower edges of the locking member and said leg having beveled edges at the upper and lower sides thereof adapted to be engaged by said locking lever extensions for shifting the legs to raise and 35 lower the upper free end of the curved bracket arm with respect to the universal joint.

6. In row lock mechanism, a mounting member, a normally horizontally disposed 40 leg pivotally mounted thereon, an upwardly extending curved bracket arm carried by

the free end of said leg, a universal joint connection for an oar disposed between the mounting member and the upper free end of the bracket arm, a locking lever pivoted 45 on the mounting member, extensions carried by the upper and lower edges of the locking member and said leg having beveled edges at the upper and lower sides thereof adapted to be engaged by said locking lever 50 extensions for shifting the legs to raise and lower the upper free end of the curved bracket arm with respect to the universal joint, and a lock carried by the locking lever adapted to engage said leg for limiting 55 the closing movement of the locking lever.

7. In a row lock mechanism, a mounting member, a normally horizontally disposed leg pivotally mounted thereon, an upwardly extending curved bracket arm carried by 60 the free end of said leg, a universal joint connection for an oar disposed between the mounting member and the upper free end of the bracket arm, a locking lever pivoted on the mounting member, extensions carried 65 by the upper and lower edges of the locking member and said leg having beveled edges at the upper and lower sides thereof adapted to be engaged by said locking lever extensions for shifting the legs to raise and 70 lower the upper free end of the curved bracket arm with respect to the universal joint, a lock carried by the locking lever adapted to engage said leg for limiting the 75 closing movement of the locking lever, and a tensioned latch device carried by the locking lever adapted for cooperation with the mounting member for holding the lever in locked position.

In testimony whereof I affix my signature. 80

WILLIAM J. TRESNAK.
